MIXING PARTITION FOR COMBUSTION CHAMBERS

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application March 22, 1947, Serial No. 736,443

1 Claim. (Cl. 60—35.6)

1

This invention relates to combustion chambers as used in propulsion apparatus and of the type having an open rearward discharge nozzle for the combustion gases. Where two combustion liquids, such as liquid oxygen and gasoline, are injected directly into a combustion chamber, it is found that the combustion is at times incomplete and that drops of fuel leave the chamber with the discharged combustion gases.

It is the general object of this invention to provide improved means for attaining more complete combustion in such a combustion chamber. More specifically, a pervious mixing partition is provided at a longitudinally intermediate point in the chamber, and the partially consumed mixture of combustion elements is caused to pass through openings or perforations in this partition which becomes highly heated as the chamber is operated.

Passage of the combustion mixture through this heated partition breaks up any drops of liquid which have not been vaporized and causes very effective intermingling of the gases and vapors. After passing through the heated partition, further and more complete combustion takes place.

The invention further relates to arrangements and combinations of parts which will be herein-after described and more particularly pointed out in the appended claim.

Preferred forms of the invention are shown in the drawing, in which

Fig. 1 is a sectional side elevation of a combustion chamber embodying this invention;

Fig. 2 is a face view of a modified partition;

Fig. 3 is an enlarged detail sectional view, taken along the line 3—3 in Fig. 2;

Fig. 4 is a view similar to Fig. 3 but showing a further modification;

Fig. 5 is a partial sectional side elevation of a combustion chamber showing an alternative construction;

Fig. 6 is an end view, looking in the direction of the arrow 6 in Fig. 5; and

Fig. 7 is a detail transverse section of one of the tubular elements shown in Figs. 5 and 6.

Referring to Fig. 1, a combustion chamber C is provided with a closed inner end portion 10 and with an open discharge nozzle 11. An igniter 12 is mounted in the end portion 10.

Liquid oxygen is fed to the chamber C through a pipe 14 and annular intake passage 15. Gasoline is fed to the chamber C through one or more feed pipes 17 and the combustion liquids intermingle adjacent the igniter 12. Cooling water may be injected through a pipe 18.

2

A partition 20 is mounted in the chamber C at an intermediate point in its length and may be retained in position by rings 21, secured to the chamber wall in any convenient manner, as by welding thereto. The partition 20 may be arched or convex as shown in Fig. 1 or may be flat as shown in Figs. 2 to 4.

The partition 20 is to be formed of heat-resistant material, such as carbon or a metal having a very high melting point, as the partition becomes very hot when the chamber is in operation. A large number of holes or perforations 22 extend through the partition 20, and these holes 22 are preferably countersunk at both ends 15 to provide easy entrance and exit to the combustion mixture passing therethrough.

Substantially complete mixing of the partially consumed combustion elements takes place as the mixture passes through the holes 22 in the partition 20. This complete mixing is due in part to the vaporizing of any drops of liquid on the surface of the heated partition 20, also to the fact that eddies cause the mixture to strike the hot surface at various angles and to the fact that 25 further combustion is facilitated by heat imparted to the mixture as it passes through the highly heated partition.

As the combustion gases approach the nozzle 11, it is desirable that any gaseous eddies be straightened out, and for this purpose vanes 40 30 may be provided at the exit end of the combustion chamber, which vanes extend radially inward and also extend longitudinally parallel to the axis of the combustion chamber and nozzle.

In the construction shown in Fig. 2, the mixing partition 50 is shown flat instead of arched and is provided with perforations 51 arranged in radial rows. The perforations 51 have countersunk entrance portions 52 as shown in Fig. 3, which figure also shows the preferred construction of the openings in the partition 20.

To prevent the possibility of drops of liquid passing directly through the openings 22 or 50, which are parallel to the combustion chamber 45 axis, the holes may be disposed at a substantial angle to the face of the partition, as indicated at 60 in the partition 61 shown in Fig. 4.

An alternative construction is shown in Figs. 5 to 7 in which the partially consumed combustion elements pass through a double grid, each 50 part of which comprises a series of tubes extending crosswise of the combustion chamber C' and at right angles to each other in the two grid parts.

One grid part comprises a series of parallel tubes 70 terminating in manifolds 71 and 72 at

each side of the combustion chamber. A feed pipe 73 supplies a cooling liquid, as water, to the manifold 71 and tubes 70 and this water is discharged from the manifold 73 through a pipe 74.

The second grid part is similarly formed of tubes 80 mounted in manifolds 81 and 82 provided with a feed pipe 83 and discharge pipe 84.

Each tube 70 or 80 is thus effectively cooled by the liquids passing therethrough. Each tube may also desirably be provided with an enclosing coating or covering of heat-resistant material, as indicated at 85 in Fig. 7.

The intersecting tubes 70 and 80 constitute a double grid which is engaged by the partially consumed combustion mixture and which causes substantially complete mixture and final combustion thereof, all as previously described with reference to the construction shown in Fig. 1.

With all the described constructions, combustion in the chamber C takes place in two steps. Initial combustion occurs in the entrance portion of the combustion chamber C, and final and substantially complete combustion takes place beyond the mixing partition or grid and as the combustion gases approach the discharge nozzle 11.

Having thus described the invention and the advantages thereof, it will be understood that the invention is not to be limited thereto, otherwise than as set forth in the claim, but what is claimed is:

In a combustion apparatus having a combustion chamber with an inner closed end portion, an initial combustion area, a final combustion area, an open rearward discharge nozzle, means to feed and commingle a liquid fuel feed and a

liquid oxidizer in said initial combustion area, means to ignite the combustible mixture in said initial area, and a pervious mixing partition positioned at a longitudinally intermediate point in said chamber and defining said areas and through which partition the partially-consumed combustion mixture is passed, whereby substantially complete mixing and vaporization thereof is effected before final combustion thereof, that improvement which comprises said pervious partition constituted of two units mounted in parallel and closely adjacent planes, with each unit consisting of a plurality of closely adjacent and parallel hollow tubes and with the tubes in each unit extending across and substantially perpendicular to the tubes in the adjacent unit.

ESTHER C. GODDARD,
*Executrix of the Last Will and Testament of
Robert H. Goddard, Deceased.*
